UNITED STATES PATENT OFFICE.

SAMUEL RUST, OF NEW YORK, N. Y.

SECTOR-PRESS.

Specification of Letters Patent No. 9,651, dated April 5, 1853.

To all whom it may concern:

Be it known that I, SAMUEL RUST, of the city, county, and State of New York, have invented certain new and useful Improvements in Sector-Presses for Compressing, Punching, Stamping, Cutting, or other Purposes for which Pressure is Required; and I do hereby declare that the following is a full, clear, and exact description of the same, 10 reference being had to the accompanying drawings, forming part of this specification, in which—

Figure 1, is a front view of a press for punching boiler iron, constructed according 15 to my improvements. Fig. 2, is a vertical section through the center taken at right angles to Fig. 1. Fig. 3, is another vertical section in a plane parallel with Fig. 1, and Fig. 4, is a partial section of the frame 20 taken at the side of the working parts.

Similar letters of reference indicate corresponding parts in each of the several figures.

The nature of my improvements consists 25 in the employment of two sectors working face to face one only being eccentric and the other an arc of a circle, the concentric sector working on a center or axis which is fixed during the pressing operation, and the 30 eccentric sector having the punch or other appendage to which the motion is to be given to obtain the pressure, hinged to it at its center or axis, and having one or more bearing pieces attached of such form and 35 in such position that as the sector is returned to relieve the punch or equivalent of the pressure the said piece or pieces will be brought in contact with a suitable rest or rests upon the press frame and by causing 40 the axis of the sector to be drawn up or back in the opposite direction to that in which it moves to give the pressure, will raise or draw back the punch or other pressing appendage. The power is applied to 45 the eccentric sector in order to make the operation of the two sectors infallible, and the axis of the concentric sector is allowed a certain amount of motion in the line of pressure to enable it to follow and keep in 50 contact and work with the eccentric sector as it is relieved of the pressure.

The principal objects which I have in view, and which I accomplish by these improvements, are to dispense with the wedge 55 or roller commonly employed between the sectors, and also with the very powerful

springs or equivalent devices employed to raise or withdraw the punch, or equivalent, and thus simplify the construction.

It is well known that in punching heavy 60 metal plate the punch remains so tightly fixed in the hole it has made as to require a very great amount of power to withdraw it, but by means of the bearing piece or pieces a moderate application of power to 65 the lever or purchase which moves the sector will never fail to effect this.

I am aware that sectors have been employed without the wedge and roller, but both have been made eccentric and when 70 such is the case if the faces are plain and power is applied to one only, it is impossible to prevent them slipping from each other, it is therefore necessary either to make them toothed, which creates friction, or apply the 75 power equally to both. I am also aware that an eccentric toothed sector and a pinion have been used in combination, and in that case the power has been applied to the pinion which is equivalent to the concentric sector; 80 but I believe that two sectors with smooth faces have never been successfully employed without the wedge or roller, and further, that the only way in which that can be done is to make one eccentric and the other concentric, and apply the power to the former, by which a more simple press than any in use is produced.

In order to render the construction and operation of my press more perfectly intelligible, I will proceed with the description, referring to the drawings.

A, is the frame which may be of any form best calculated for strength. B, is the punch which works vertically in a suitable guide in the frame—the piston, platen, or follower, will be similarly placed in other presses. C, is the eccentric sector hinged at its axis *a*, to the punch. D, is the concentric sector whose axis is formed by a pin *b*, which while the 95 pressure is being given bears in a suitable recess under the head *E*, in the same vertical plane as the center of the punch. The pin *b*, hangs in an eye-bolt *d*, which works vertically through the head *E*, and its ends fit 100 easily in vertically elongated recesses *c*, *c*, between ribs in the sides of the frame. The sector *D*, is attached to the pin *b*, by light ears *g*, *g*. The pin may be hung in two eye-bolts one at each end working similarly to 110 *d*, then the recesses *c*, *c*, will not be necessary. The two sectors are provided with locking

pieces *e*, *f*, which bring them into proper relation with each other, after the withdrawal of the punch or its equivalent, in case through any irregularity they should work out of place.

F, *F*, are two bearing pieces for withdrawing the punch, they may be cast with or be bolted to the sector *C*, being both alike and occupying corresponding positions, *h*, *h*, are shoulders on the frame *A*, for the bearing pieces *E*, *F*, to act upon. If only one bearing piece is used it will be placed in front of the sector near the center of the press and will act upon a rest in front of the punch or 15 pressing apparatus. *H*, is a lever which is shaped at its end in a suitable manner to be easily shipped and unshipped in a recess in the back of the sector *C*, and is for the purpose of applying the power to work the 20 press.

When the punch is raised the lever *H*, occupies the upward position shown in the drawings. To apply the pressure, the weight of the operator is applied to the lever to 25 bring it and the sectors to the position shown in Fig. 2, in red color. The raising of the lever to relieve the sectors throws down the bearing pieces *F*, *F*, upon the rests *h*, *h*, and the latter serve as a fulcrum to the bearing 30 pieces and enable them to raise the punch; it is obvious that with a long lever great power may be applied in raising the punch, without much effort on the part of the operator.

In case the bearings *F*, *F*, do not at all 35 points or parts raise the sector *C*, exactly to keep up tight against the top sector *D*, by the striking of the punch or otherwise, I have made the axes *b*, to move in the line of the pressure to or from the axes *a*, this move- 40 ment being allowed, the weight of *D*, will always keep its face in contact with *C*, and the latter cannot return as the lever is raised without causing *D*, to do the same and therefore can not work out of proper relation to 45 each other to a greater extent than the locking pieces *f*, *e*, will adjust.

What I claim as my invention and desire to secure by Letters Patent, is—

1. One or more bearing pieces *F*, *F*, at 50 the sides or in front of the eccentric sector *C*, acting upon any fixed point or rest as at *h*, *h*, on the press frame, for the purpose of raising or withdrawing the punch or pressing appendage, by power applied to the 55 sector in the reverse direction to that by which the pressure is given substantially in the manner specified.

2. I claim allowing to the concentric sector a sufficient amount of motion directly in 60 the line of the pressure to enable it to follow and always keep in contact and in proper relation to the eccentric sector substantially as herein set forth.

SAMUEL RUST.
